Primary Examiner — Darlington Ly(74) *Attorney, Agent, or Firm* — Faegre Drinker Biddle & Reath LLP(57) **CLAIM**

The ornamental design for a motorcycle, as shown and described.

DESCRIPTION

FIG. 1 is a top, front, and left side perspective view of a motorcycle showing our new design;

FIG. 2 is a top, rear, and right side perspective view thereof;

FIG. 3 is a partial top, rear, and right side perspective view thereof;

FIG. 4 is a left side elevation view thereof;

FIG. 5 is a right side elevation view thereof;

FIG. 6 is a top plan view thereof;

FIG. 7 is a front elevation view thereof; and,

FIG. 8 is a rear elevation view thereof.

The broken lines in the drawings illustrate portions of the motorcycle that form no part of the claimed design.

1 Claim, 7 Drawing Sheets# US D911,879 S
